DESIGN FOR A COMMUNICATIONS UNIT OR THE LIKE

Leo J. Hruska, Lutherville, and William W. Gar-
butt, Baltimore, Md., assignors to Bendix Avia-
tion Corporation, Towson, Md., a corporation
of Delaware

Application November 4, 1946, Serial No. 134,497

Term of patent 3½ years

(Cl. D26—14)

To all whom it may concern:

Be it known that we, Leo J. Hruska and Wil-
liam W. Garbutt, citizens of the United States,
residing at Lutherville, county of Baltimore, State
of Maryland, and city of Baltimore, respectively,
have invented a new, original, and ornamental
Design for a Communications Unit or the like, of
which the following is a specification, reference
being had to the accompanying drawings, forming
a part thereof.

In the drawings:

Figure 1 is a front oblique view of a communi-
cations unit or the like, showing our new design;
and

Figure 2 is a back oblique view thereof.

The dotted line portions of the drawing are
for illustrative purposes only.

What is claimed is:

The ornamental design for a communications
unit or the like, as shown and described.

LEO J. HRUSKA.

WILLIAM W. GARBUTT.
